UNITED STATES PATENT OFFICE

WILLIAM FORSTNER, OF IRVINGTON, NEW JERSEY, ASSIGNOR TO FORSTNER CHAIN CORPORATION, OF IRVINGTON, NEW JERSEY, A CORPORATION OF NEW JERSEY

DESIGN FOR A FLEXIBLE METALLIC STRAP

Application filed April 30, 1930. Serial No. 35,445. Term of patent 14 years.

To all whom it may concern:

Be it known that I, WILLIAM FORSTNER, a citizen of the United States, residing at Irvington, in the county of Essex and State of New Jersey, have invented a new, original, and ornamental Design for a Flexible Metallic Strap, of which the following is a specification, reference being had to the accompanying drawing, forming part thereof.

I claim:

The ornamental design for a flexible metallic strap, as shown.

WILLIAM FORSTNER.
